UNITED STATES PATENT OFFICE.

ROBERT CAMERON, OF PHILADELPHIA, PENNSYLVANIA.

HAME.

SPECIFICATION forming part of Letters Patent No. 340,697, dated April 27, 1886.

Application filed September 19, 1885. Serial No. 177,521. (No model.)

To all whom it may concern:

Be it known that I, ROBERT CAMERON, a citizen of the United States, residing at Philadelphia, in the county of Philadelphia and State of Pennsylvania, have invented certain new and useful Improvements in Hames; and I do hereby declare the following to be a full, clear, and exact description of the invention, such as will enable others skilled in the art to 5
10 which it appertains to make and use the same.

My invention relates to silver and brass mounted iron hames; and the improvement consists in inclosing the upper end of the hame, which has been previously drawn down to the 15 required size and shape, with a brass or other metal shell, which may be electroplated upon the ordinary way. As electroplating direct'y upon iron is apt to scale off, heretofore when desiring to silver-plate hames of this class the 20 part to be plated was carefully filed down and finished off, and then covered with a thin coating of tin, upon which the silver-leaf was laid and secured in position by passing a hot iron over the surface of the silver, this being the 25 old-fashioned way of plating.

When the hame-top is covered with the brass shell, the careful filing and finishing of the iron part to be plated becomes entirely unnecessary, and the brass covering can be easily 30 and quickly prepared for electroplating, thus accomplishing a saving of time, labor, and expense.

In the accompanying drawings, Figure 1 represents a finished pair of hames having my 35 improvement thereon. Fig. 2 shows a hame-top with the open brass shell fitted thereon. Fig. 3 shows the iron top of the hame finished to receive the brass shell. Fig. 4 is the brass shell.

40 A represents the main body of the hame,

which may be wholly or partially made of iron. a is the drawn-down top, having formed thereon the shoulder a'. b is the brass shell or covering, which is made of any desired length, and of a shape to conform to the hame-top. b' 45 is a ball tip or finish on the end of the hame.

The method of making my improved hame is as follows: The iron top of the hame is first drawn down and shaped, as shown in Fig. 3, when the brass shell (shown in Fig. 4) is placed 50 thereon in the manner shown in Fig. 2. The edges of the shell are then pressed or hammered together, so that they meet around the hame-top, after which the ball-tip is placed on the end of the hame, which extends through 55 and projects beyond the shell to receive said ball, thus securely fastening the shell in position. The brass shell being finished off, the hame is then ready for plating; or, if desired, it may be burnished and used without plating. 60

Having thus described my invention, what I claim as new, and desire to secure by Letters Patent of the United States, is—

1. The hame A, having the drawn-down top a, in combination with the metal shell b and 5: a fastening means on the end of the hame that projects beyond the said shell, substantially as and for the purpose set forth.

2. The hame A, having the drawn top a and shoulder a', in combination with the metal 7: shell b and a part, as b', placed upon the end of the hame which projects through the shell, to secure said shell in place, substantially as shown and described.

In testimony whereof I affix my signature in 7: presence of two witnesses.

ROBERT CAMERON.
